(57) CLAIM

I claim the ornamental design for the floor located vehicle container, as shown and described.

DESCRIPTION

FIG. 1 is a general perspective view of a container holder designed according to the present invention;

FIG. 2 is a general top perspective view of a container holder designed according to the present invention;

FIG. 3 is a general side perspective view of a container holder designed according to the present invention;

FIG. 4 is a general front perspective view of a container holder designed according to the present invention; and,

FIG. 5 is a general back perspective view of a container holder designed according to the present invention.

The broken line showing of openings is for illustrative purposes only and forms no part of the claimed design.

The contrasting shading shown on the inside of the claimed design represents fabric covering the inside surface.
